SLIDE FASTENER

Peter Weber, Koblenz, Germany

Application February 8, 1954, Serial No. 28,916

Term of patent 7 years

(Cl. D17—8)

FIG. 1.

FIG. 2.

To all whom it may concern:

Be it known that Peter Weber, a citizen of the Federal Republic of Germany, residing at Koblenz, Germany, has invented a new, original, and ornamental Design for a Slide Fastener, of which the following is a specification, reference being had to the accompanying drawing, forming part thereof.

Fig. 1 is a plan view of a slide fastener, showing my new design;

Fig. 2 is a side view thereof.

I claim:

The ornamental design for a slide fastener, as shown.
